UNITED STATES PATENT OFFICE.

JOSÉ SIERRA V., OF SAN FRANCISCO, CALIFORNIA.

SOAP COMPOSITION.

No. 901,204.

Specification of Letters Patent.

Patented Oct. 13, 1908.

Application filed March 11, 1908. Serial No. 420,383.

To all whom it may concern:

Be it known that I, JOSÉ SIERRA V., a citizen of Guatemala, residing in the city and county of San Francisco and State of California, have invented a new and useful Improvement in Soap Composition, of which the following is a specification in such full and clear terms as will enable those skilled in the art to construct and use the same.

10 My invention relates to soaps and has for its object to provide in an article of that class an ingredient which will make the same agreeable to the skin, which will preserve the hair and cleanse the scalp.

15 I have discovered that the pulp of the alligator pear, the *Laurus persea*, possesses the properties which I desire to impart to my soap. In other words, I have discovered that the combination with saponaceous materials 20 of the pulp of the alligator pear will give to the resulting compound the qualities above named.

25 My compound comprises in general terms the combination with a mixture of detergent materials such as olive oil, fine table salt and caustic soda, of the pulp of the alligator pear.

The proportions are as follows: olive oil 30 per cent., fine table salt 5 per cent., caustic 30 soda 20 per cent., pulp of the alligator pear

25 per cent. The above named proportions may be departed from without destroying the desired effects of my compound.

The ingredients are mixed together in preparation and heated. Said mixture and heating causes the caustic soda to saponify 35 the olive oil, forming soap and glycerin, with an excess of caustic soda.

Having described my invention what I claim as new and desire to secure by Letters 40 Patent of the United States, is:

1. A soap composition consisting of soap, glycerin, fine table salt, caustic soda and the pulp of the alligator pear.

2. A soap composition consisting of olive 45 oil fifty percent. and caustic soda twenty percent. mixed and heated to form soap and glycerin with an excess of caustic soda, fine table salt five per cent., and the pulp of the alligator pear twenty-five per cent.

3. A soap composition consisting of the combination with soap of the pulp of the alligator pear.

50 In testimony whereof I have set my hand this 4th day of March A. D. 1908, in the 55 presence of the two subscribed witnesses.

JOSÉ SIERRA V.

Witnesses:

FRANK P. MEDINA,
EDITH W. BURNHAM.
